WILLIAM L. BUTCHER, OF NEWTON, MASSACHUSETTS, ASSIGNOR TO THE BUTCHER POLISH CO., OF BOSTON, MASSACHUSETTS, A CORPORATION OF MASSACHUSETTS

COMBINATION WAX DISTRIBUTOR AND POLISHER

Application filed January 26, 1928. Serial No. 249,680.

The invention relates to a combination implement or tool by which liquid wax may be applied to a floor and the wax afterward rubbed down and the floor polished. The invention contemplates the using of a receptacle or container for the liquid wax and an instrument in the nature of a mop with handle by which the liquid wax may be removed from the container and applied to the floor.

10 One object of the invention is to provide a construction whereby the mop with handle and the receptacle may be brought together and combined and thereby co-operate to form the polishing instrument.

15 Where an instrument like a mop is used for applying liquid wax to a floor, the wax left on the mop after it has been used tends to evaporate and harden making the mop, usually consisting of some soft flexible material, 20 practically useless until it has been cleansed or freed from the stiffened wax. Another object of the invention is to obviate this difficulty.

A still further object of the invention is to 25 provide whereby the mop when dipped in the wax container may be charged only with a proper amount of liquid wax for application to the floor. In other words, the purpose in this connection is to provide means whereby 30 just the proper amount of wax will be applied to the floor for obtaining the best results instead of dousing the floor with wax as is oftentimes the case.

The invention contemplates also other useful purposes in connection with a combination tool of this kind especially where the several parts are combined to form a polishing instrument, all of which can best be seen and 35 understood when explained in the light of the drawings, in which—

Figure 1 is a section on the line 1—1 of Fig. 2.

Fig. 2 is a plan of the device with its separate parts, viz: the wax container and mop with handle combined, forming the polishing instrument.

Fig. 3 is a cross section of the wax receptacle with the mop disconnected therefrom, 50 and

Fig. 4 is a cross section of the mop with a part thereof shown in elevation.

1 represents a combination wax container and polishing foot. This comprises a receptacle preferably rectangular in form made of metal plate, the bottom wall of the receptacle being preferably heavier in metal than that forming the other walls.

Liquid wax is introduced into the chamber of the receptacle by way of an opening 2 in its top wall. This opening is normally closed by a filling plug 3 having an airtight fit.

Located at about the middle of the receptacle and preferably extending crosswise thereof is an open trough 4. The trough is relatively narrow compared with the length of the receptacle and the length of the trough is preferably less than the width of the receptacle. The open top of the trough is substantially flush with the top wall of the receptacle and in depth the trough extends substantially to the bottom of the receptacle. The trough comprises converging side walls 5 and 6, respectively, while 7, 7 represent its end walls. All of these walls 5, 6 and 7, 7 of the trough have closed connection with the top wall of the receptacle. The converging side wall 5 of the trough terminates along a bottom edge 8 spaced from the bottom of the receptacle leaving an opening 9 from the chamber of the receptacle into the trough. The converging side wall 6 of the trough is provided with an extension 10 which projects downward and has closed connection with the bottom wall of the receptacle. The end walls 7, 7 of the trough have closed connection with its converging side wall 5 and also with the converging side wall 6 and its extension 10. With the walls of the trough thus arranged entry into the trough from the chamber of the receptacle is only by way of the opening 9 and accordingly liquid wax contained within the receptacle and flowing into the trough cannot rise therein above the edge 8 of the trough which forms the top of the opening 9 even though the level of liquid wax within the receptacle is above this edge.

This is due to the fact that air cannot enter the chamber of the receptacle after the liquid wax has filled the bottom of the trough 100

up to the point of the edge 8. Thus it will be seen that a comparatively little amount of liquid wax has permitted entry into the trough so that the mop may take up comparatively little wax at any one time, but to this reference will be made at a later point.

Connecting with the top wall of the receptacle and projecting upwardly therefrom with extension all around the trough 4 in the receptacle is a comparatively high wall 12 forming an enclosure. This wall co-operates with the top wall of the receptacle to form a relatively wide deep chamber 13 within which a mop 14 may be contained.

The mop 14 consists of various fibrous strands or pieces like an ordinary mop and these pieces are secured to a head 15 to the upper face of which is secured a handle 16. The head 15 of the mop forms the bottom part of a deeply dished plate 17 and the mop is secured to the head to lie beneath this plate so that when the mop is contained to lie within the chamber 13 the plate 17 will have projection to extend over the top edge of the wall enclosure 12, thereby forming a cover for it and closing the chamber 13 and mop lying within it from the atmosphere. In order that the mop may be secured to the head to lie beneath the plate 17, the head 15 is preferably made cylindrical so that the pieces forming the mop bound together may be wrapped around it and secured to it by pins 18 or other suitable means of fastening. In order that the plate 17 or cover may be properly centered to fit on the top of the enclosing wall 12, the plate is provided with an edge or flange 19 which turns down outside the top end portion of the wall 12 when the cover is in place.

The mop is inserted into the chamber 13 through the open top end of the enclosure 12 and the arrangement of the parts is such that when the mop is in place within the chamber of the enclosure no part or strand of the mop will lie on the top edge of the enclosure for if any part of the mop be left to extend over said edge when the cover is on, it will prevent a proper substantially airtight joint between the cover and the top edge of the enclosure 12. The arrangement of the parts is also such that when the mop is inserted into the chamber of the enclosure all parts of the mop will drop to the bottom of the chamber and seat themselves on the top of the liquid wax containing receptacle with some portion of the mop lying within the open trough 4. All this is initially provided for by dishing the plate 17 as aforesaid so that the head 15 to which the mop is secured will occupy a position relatively deep down in the chamber 13 when the cover is in place, then by making the strands of the mop of such length that they cannot reach the edge of the enclosure when the cover is in place and the head of the mop positioned as aforesaid no strand

or portion of the mop will be left on the top edge of the enclosure to prevent a tight fit of the cover. To permit of all strands of the mop dropping to the bottom of the chamber on the introduction of the mop into it, the head to which the mop is secured is spaced all around from the enclosing wall 12.

The cover when in place is held securely locked onto the wall 12 by means of spring slips 20 secured to said wall. These slips are adapted to have locking engagement with an outstanding ring 21 on the bottom edge of the downturned flange 19 of the cover. In order that the cover may be released from these slips, one of them is provided with an outstanding foot or lever 22 which may be depressed thereby turning the clip away from the ring with which it has locking engagement and permitting removal of the cover.

The handle 16 is preferably pivotally secured to the head of the mop. To this end the handle is fitted with a ferruled piece 24 having trunnions 25 which turn in strap holders 26 on the top side or face of the head 15 of the mop.

The operation of the device is as follows: In the first place it will be assumed that the mop is being used for applying liquid wax to a floor. In such case the wax will be applied to the mop by dipping the mop into the trough 4 of the wax containing receptacle. In this way very little wax will be applied to the mop at any one time owing to the relatively small size of the trough and the fact that very little wax is contained in it although the trough is kept continuously filled to the limit of its capacity. Thus while a proper amount of wax is applied to the mop for application to the floor, yet the mop is kept from being so saturated with the wax that too much wax will be applied to the floor. What is wanted for effective polishing is a thin coating of wax and not a dousing of the floor with wax.

After the wax has been applied to the floor by the mop, the mop is inserted within the chamber formed by the enclosing wall 12 and the cover 17 applied and locked on. The mop and its attached parts then become so connected with the wax holding receptacle that all may be moved together, the wax containing receptacle then becoming a polishing foot which may be moved over the surface of the waxed floor by the handle of the mop for purposes of polishing.

In order that the wax containing receptacle may properly function as a polishing instrument, it is fitted on its under side with a polishing pad 28 and this is held in place by a cloth or holder 29 which fits over the entire wax containing receptacle or foot and laps onto the top side or surface thereof by portions 30 sewed together along their meeting edges 31, the entire cloth holder being thereby tightened onto the wax containing

receptacle for holding the pad securely in place.

After the polishing operation has been completed the mop is left within the chamber 13 then closed by the cover. Under these circumstances little or no air can enter the chamber and consequently the wax left on the mop after it has been used will not evaporate and harden, and therefore the mop will be ready for further use at any time 10 without the necessity of cleansing.

Having thus fully described my invention, I claim and desire to secure by Letters Patent of the United States:—

1. The combination comprising a liquid 15 wax containing receptacle having an open trough in the top wall thereof in communication with the interior of the receptacle whereby liquid wax therein may flow into the trough, an enclosure forming wall around said trough co-operating with the top wall of the receptacle to form a chamber with an open top through which a mop may be introduced to lie within said chamber seated on the top wall of the receptacle and lying in 20 part within said trough, a mop capable of being introduced into said chamber and seated as aforesaid, a cover connected to the mop and adapted to close the top of said chamber when the mop is contained therein as aforesaid, and releasable means for holding 25 the cover in place.

2. The combination comprising a liquid 30 wax containing receptacle having an open trough in the top wall thereof in communication with the interior of the receptacle whereby liquid wax therein may flow into the trough, an enclosure forming wall around said trough co-operating with the top wall of the receptacle to form a chamber with an open top through which a mop may be introduced to lie within said chamber seated on the top wall of the receptacle and lying in 35 part within said trough, a mop capable of being introduced into said chamber and to become seated therein as aforesaid, and a cover capable of closing the top of said chamber when the mop is contained within the chamber.

3. The combination comprising a liquid 40 wax containing receptacle having an open trough in the top wall thereof in communication with the interior of the receptacle whereby liquid wax therein may flow into the trough, an enclosure forming wall around said trough co-operating with the top wall of the receptacle to form a chamber with an open top through which a mop may be introduced to lie within said chamber seated 45 on the top wall of the receptacle and lying in part within said trough.

4. The combination comprising a liquid 50 wax containing receptacle adapted also to function as a polishing foot, said receptacle having an open trough in the top wall there-

of in communication with the interior of the receptacle whereby liquid wax therein may flow into the trough, an enclosure forming wall around said trough co-operating with the top wall of the receptacle to form a chamber with an open top through which a mop may be introduced to lie within said chamber seated on the top wall of the receptacle and lying in part within said trough, a mop capable of being introduced into said chamber and seated as aforesaid, and a handle connected to the mop extending outside said chamber when said mop is contained within the chamber.

5. The combination comprising a liquid 55 wax containing receptacle adapted also to function as a polishing foot, said receptacle having an open trough in the top wall thereof in communication with the interior of the receptacle whereby liquid wax therein may flow into the trough, an enclosure forming wall around said trough co-operating with the top wall of the receptacle to form a chamber with an open top through which a mop may be introduced to lie within said chamber seated on the top wall of the receptacle and lying in part within said trough, a mop capable of being introduced into said chamber and seated as aforesaid, a handle connected to the mop extending outside said chamber when said mop is contained within the chamber, a cover connected to the mop and adapted to close the top of said chamber when the mop is contained within the chamber, and releasable means for holding the cover in place.

6. The combination comprising a liquid 60 wax containing receptacle having an open trough in the top wall thereof in communication with the interior of the receptacle whereby liquid wax therein may flow into the trough, an enclosure forming wall around said trough co-operating with the top wall of the receptacle to form a chamber with an open top through which a mop may be introduced to lie within said chamber seated on the top wall of the receptacle and lying in part within said trough, a mop capable of being introduced into said chamber and to become seated therein as aforesaid, a head 65 to which said mop is secured, said head and attached mop bearing such relation to said enclosure that the mop may be introduced into the enclosure and seated as aforesaid and no portion of the mop be then left to rest upon the top edge of said enclosure, and a cover adapted to fit over the top edge of said enclosure closing said chamber when the mop is contained and seated therein as aforesaid.

7. The combination comprising a liquid 70 wax containing receptacle having an open trough in the top wall thereof in communication with the interior of the receptacle whereby liquid wax therein may flow into the trough, an enclosure forming wall

around said trough co-operating with the top wall of the receptacle to form a chamber with an open top through which a mop may be introduced to lie within said chamber seated on the top wall of the receptacle and lying in part within said trough, a mop capable of being introduced into said chamber and seated as aforesaid, a head with attached handle to which said mop is secured, said head and attached mop bearing such relation to said enclosure that the mop may be introduced into the enclosure and seated as aforesaid and no portion of the mop be then left to rest upon the top edge of said enclosure, a cover connected to the head of the mop and adapted to close the top of said chamber when the mop is contained and seated therein as aforesaid, and releasable means for then holding the cover in place.

20 8. The combination comprising a liquid wax-containing receptacle having an opening in the top wall thereof through which access is had to the liquid wax contained within the receptacle, an enclosure-forming wall around said opening with an open top through which a mop may be introduced into said enclosure, a mop capable of being introduced into said enclosure, and means forming a combination head for the mop and cover for the enclosure with said head of the mop depressed to lie within said enclosure when the cover is in place.

25 9. The combination comprising a liquid wax-containing receptacle adapted to function also as a polishing foot, said receptacle having an opening in the top thereof through which access is had to the liquid wax contained within the receptacle, an enclosure-forming wall around said opening with an 30 open top through which a mop may be introduced into said enclosure, a mop capable of being introduced into said enclosure, means forming a combination head for the mop and cover for the enclosure with said 35 head of the mop depressed to lie within said enclosure when the cover is in place, releasable means for holding the cover in place, and a handle secured to the head of the mop.

40 10. The combination comprising a liquid wax-containing receptacle having an open trough in the top wall thereof, said trough being of relatively restricted area and connecting with the interior of the receptacle whereby liquid wax therein will flow outwardly therefrom into said trough, means whereby liquid wax contained within the receptacle and entering said trough from the interior of the receptacle will rise in the trough only to a determinate height, an enclosure-forming wall around said trough co-operating with the top wall of the receptacle to form a chamber with an open top through which a mop may be introduced to lie within said chamber seated on the top wall of the receptacle and lying in part within said

trough, and means for closing the top end of said chamber when the mop is seated within it as aforesaid.

11. The combination comprising a liquid wax-containing receptacle having an open trough in the top wall thereof, said trough being of relatively restricted area and connecting with the interior of the receptacle whereby liquid wax therein will flow outwardly therefrom into said trough, means whereby liquid wax contained within the receptacle and entering said trough from the interior of the receptacle will rise in the trough only to a determinate height, an enclosure-forming wall around said trough co-operating with the top wall of the receptacle to form a chamber with an open top through which a mop may be introduced to lie within said chamber seated on the top wall of said receptacle and lying in part within said trough, a mop capable of being introduced into said chamber and seated therein as aforesaid, and means forming a combination head for the mop and cover for said enclosure when the mop is contained within its chamber and seated in it as aforesaid.
